UNITED STATES PATENT OFFICE.

LOUIS NEUBERGER, OF BRIDGEPORT, CONNECTICUT.

SUSPENDER CAST-OFF.

SPECIFICATION forming part of Letters Patent No. 651,579, dated June 12, 1900.

Application filed April 6, 1900. Serial No. 11,845. (No model.)

To all whom it may concern:

Be it known that I, LOUIS NEUBERGER, a citizen of the United States, and a resident of Bridgeport, in the county of Fairfield and 5 State of Connecticut, have invented certain new and useful Improvements in Cast-Off Suspender-Ends, of which the following is a specification.

My invention relates to new and useful improvements in suspender-ends, and refers especially to improved means for connecting the web and the buttons upon the trousers.

It is the object of my invention to improve upon devices of the above class by providing means whereby a freer self-adjustment of the suspender to the wearer is afforded and means for rendering a uniform strain upon the buttons; further, to provide a double-cord connection for the cast-off, whereby two 20 engaging surfaces are produced instead of one, and, furthermore, whereby thinner cords can be employed, and, finally, to produce an end which is neat and attractive in appearance and otherwise generally desired by the 25 trade.

With the above objects in view my invention resides and consists in the novel construction and combination of parts shown upon the accompanying drawings, forming a 30 part of this specification, upon which similar characters of reference denote like or corresponding parts throughout the several figures, and of which--

Figure 1 shows a front elevation of my improved suspender-end. Fig. 2 shows a detail side elevation of the double roller-bearing cast-off shown in Fig. 1. Figs. 3 and 4 show front and side elevations, respectively, of a slightly-modified form of roller-bearing, the 40 same comprising a structure which is permanently attached to the loop.

Referring in detail to the characters of reference marked upon the drawings, A indicates one end of a suspender-web, and B a buckle by means of which the length of said web is adjusted to suit the wearer in the usual manner.

C represents a wire loop which is retained in the folded end of the web and to which 50 the cast-off D is attached.

In Figs. 1 and 2 I have shown the cast-off detachably connected to the loop, while in

Figs. 3 and 4 it will be seen that it is fixed thereto. The cast-off, as will be seen, comprises a casing formed of a single piece of 55 sheet metal folded in its middle and bent together, the two parts being retained in their relative positions by means of studs E, upon which rollers F and G are free to rotate. The longer end of the casing is provided with 60 ears H upon either side and a return end I, which latter in practice engages the loop before referred to. The opposite end J of the casing forms a spring-like tongue and operates between the ears before mentioned in 65 such a manner as to permit of the ready attachment or detachment of the cast-off to the loop C before mentioned.

In Figs. 3 and 4 it will be seen that the construction of the upper end of the casing of 70 the cast-off differs slightly from that shown in the other figures, since it is not made detachable, but is permanently secured to the loop. The actual difference of construction in this device resides simply in the swaging 75 down of the ends of the casing upon the loop instead of the employment of the snap-hook construction shown in the other figures.

The studs E are arranged one above the other, and the upper one contains a roller F, 80 which is slightly larger than the one below it, thus permitting the cords to properly free themselves as they operate over said rollers, as will be obviously noted from Fig. 1. The cords which operate over these rollers in 85 practice really constitute a single length; but for convenience of description I will designate them as the "upper" and "lower" cords K and L, respectively. These cords are secured together down near their lower extremity by means of metallic clips M and form buttonhole-loops N, as shown.

From the above description it will be noted that the rollers as arranged permit the cords to freely slide to and fro through the casing 95 and allow the parts to readily adjust themselves to the various positions of the roller and likewise distribute the wear substantially even upon the two cords and, furthermore, insure a temporary retention by one 100 should the second become weak or broken.

Having thus described my invention, what I claim, and desire to secure by Letters Patent, is--

In a suspender-end of the class described the combination with a cast-off the same comprising a casing, central studs to retain said casing together, ears bent up from the side 5 of one end of said casing, and a hook formed by the central portion of said end, a tongue formed by the opposite end of said casing and adapted to operate in conjunction with said hook, and rollers upon the studs of said casing and arranged one above the other, cords adapted to operate on said rolls, the outer

portions of said cords being united to form a buttonhole-loop, substantially as shown and described.

In testimony whereof I have signed this 15 specification in the presence of two subscribing witnesses.

LOUIS NEUBERGER.
